CLAIM

The ornamental design for a backpiece of a national costume, as shown and described.

DESCRIPTION

FIG. 1 is a top plan view of the backpiece of a national costume showing my new design; and,

FIG. 2 is a view thereof from the side opposite that shown in FIG. 2.

The article whose design is claimed is a piece of cloth of negligible thickness. Therefore, all the side elevational views are single straight lines.

The thick black lines in FIG. 1 are seams and form a contrast and are not shading.
